(57) **CLAIM**

The ornamental design for a tire, as shown and described.

DESCRIPTION

FIG. 1 is a front perspective view of a tire, showing our new design;

FIG. 2 is a sectional view taken along line 2—2 in FIG. 3 thereof;

FIG. 3 is a right side view, the left side being a mirror image thereof; and,

FIG. 4 is a top view, the bottom view being a mirror image thereof.

In the drawings, the broken line showing of a tire rim depicts environmental subject matter and forms no part of the claim.
